LEO J. GRUBMAN, OF BELLE HARBOR, NEW YORK, ASSIGNOR TO VOICES, INCORPORATED, OF NEWARK, NEW JERSEY, A CORPORATION OF DELAWARE.

SOUND-PRODUCING DEVICE.

Application filed December 17, 1924. Serial No. 756,434.

This invention relates to sound producing devices, and more particularly to that type of sound producing devices or "voices" of more or less recent development in the art, 5 wherein there is provided within a suitable casing or housing a sound receiving chamber and a gravity movable air expelling member or head, provided with means for automatically controlling the emission of the 10 sound produced by the expulsion of air from said chamber through a reed, for the purpose of articulating the sound and simulating the characteristic cry of the doll or other toy, such as the word "ma ma".

15 The primary object and purpose of my present improvements is to provide a sound emission control means for such "voices" whereby during a single uninterrupted movement of the air expelling member, the 20 articulation of a plurality of phonetically different words is successively simulated. As an example, I propose to provide such a device, whereby during the first portion of the gravity movement of the air expelling 25 member, the word "ma ma" is sounded and thereafter during the remaining portion of the movement of said member, the word "pa pa" is sounded. I further propose to provide a sound controlling means which is so 30 constructed that by resorting to very minor changes in the parts thereof, various combinations of the word syllables "ma" and "pa" may be simulated.

35 In one practical embodiment of the invention, I provide a tubular sound emission chamber having an orifice in its wall, and a part on the gravity movable air expelling member slidably engaged with said chamber wall and having means cooperating with the 40 orifice therein to control the emission of the sound and effect the simulation of one word. In conjunction with this control part, a second sound emission controlling element is 45 slidably engaged upon the wall of said sound chamber and connected to the air expelling element by means operating to delay or retard the movement of said element during the first part of the air expelling movement of said member, and thereafter cause the 50 said element to move with said member and cooperate with the sound emission orifice to simulate the phonetic articulation of a different word.

55 It is a further general object of my invention to provide an improved sound producing device or "voice" of the above character,

greatly vary from such devices now in practical use and in which the additional elements employed are of exceedingly simple form 60 and construction so that the production and selling cost of the new device is maintained at a comparatively low figure.

With the above and other objects in view, 65 the invention consists in the improved sound producing device, and in the form, construction and arrangement of its several parts as will be hereinafter more fully described, 70 illustrated in the accompanying drawings and subsequently incorporated in the subjoined claims.

In the drawing wherein I have illustrated 75 one simple and satisfactory embodiment of the invention and in which similar reference characters designate corresponding parts throughout the several views,—

Figure 1 is a vertical sectional view illustrating the relative position of the several parts of the device at the end of the movement of the air expelling member in one direction,

80 Figure 2 is a similar view showing the relative positions of the parts when said member has reached the end of its movement in the opposite direction,

85 Figure 3 is a horizontal sectional view taken on the line 3—3 of Figure 2,

Figure 4 is a similar section taken on the line 4—4 of Figure 2, and

Figure 5 is an end elevation.

90 For purposes of illustration in the accompanying drawings, I have shown a familiar type of "voice" or sound producing device wherein the several operative parts are enclosed within a housing or casing having a body wall 5 of cardboard or other suitable material and preferably of cylindrical form, the opposite ends of this casing being provided with suitable end plates or caps 6 and 7 respectively.

95 In this instance, I have shown one end edge of a cylindrical flexible bellows wall 8 fixedly clamped or held between a marginal flange on the cap 6 and the wall of the casing 5. The other end edge of this tubular bellows wall surrounds a gravity movable head or air expelling member 9 and is suitably fixed and permanently secured to the marginal portion thereof, as shown at 10. This 100 weighty air expelling member or head is centrally provided with an opening therein and a sound emission controlling sleeve 9'

projects from the outer side of the member 9 in concentric relation with said opening. Through this sleeve and the air chamber formed by the collapsible bellows wall 8, a tubular post 11 extends. At its opposite ends, this post may be centrally fixed or held in connection with the casing ends 6 and 7 in any approved manner.

The wall of the tube 11 at one of its ends 10 is provided with an aperture 12 affording communication between the bellows chamber and the interior of said tube and within this end of the tube, the sound producing reed 13 is suitably mounted.

15 At a point in spaced relation to the other end of the tube 11, the opposed circumferentially extending slots or openings 14 are provided in the wall thereof through which the sound is emitted from the interior of said tube into a sound receiving chamber of constant definite dimensions formed within one end of the casing by a sound amplifying wall 15. This sound amplifying wall, as herein shown, constitutes no essential part of my present improvements, and, if desired, may be eliminated.

The sound emission control sleeve 9' on the weighty member 9 is provided intermediate of its ends with diametrically opposed 30 openings 16 in the wall thereof of substantially the same circumferential extent as the slots 14 in the wall of the tube 11. The wall of the sleeve 9' is further provided interiorly thereof with longitudinally aligned grooves 35 or channels 17 and 18 respectively communicating with one of the openings 16 at opposite sides thereof. These grooves are also in line with one of the slots 14 in the wall of the tube 11 and it will be noted that the groove 17 in the inner part of the sleeve is of greater length than the groove 18.

In addition to the sound control sleeve 9', a second sound emission controlling element 45 19 structurally separate from said sleeve is loosely engaged upon the tubular post 11 for free sliding movement. This element 19 is relatively short and is likewise provided intermediate of its ends and at diametrically opposite points with the openings 20 which are in longitudinal alignment with the openings 16 in the wall of the sleeve 9'.

The expansion coiled spring 24 surrounds the sleeve 9' and the element 19 has one of its ends suitably fixed as at 21 to the weighty head or member 9 and the other end thereof is suitably secured, as at 22, to the element 19.

The wall of the end cap or plate 7 on the casing is provided with the usual sound emission openings 23 therein.

In the operation of the device above described, when said device is arranged in the position shown in Figure 1 of the drawings, the end of the sleeve 9' is engaged against 65 one end of the element 19, which is held

under the weight of the member 9 against the metal cap or cover 7 on the casing. In this position, the bellows chamber is fully inflated with air and it will be observed that one of the slots 14 in the wall of the tubular 70 post 11 registers with the inner end of the slot 17 in the wall of the sleeve 9'.

When the device is inverted from the position shown in Figure 1, the weighty head or member 9 immediately starts to move downwardly by gravity on the tube 11 and expel the air from the bellows chamber through orifice 12 and the sound producing reed 13. In the initial movement of the member 9, the sleeve 9' thereof moves away from the element 19 which is held relatively stationary under the expansive pressure of the spring 24, while the sound escapes from the interior of the tube in relatively small volume through the opening 14 in the tube wall, slot 17 and one of the openings 16 in the sleeve 9' and simulates the sound of the letter "m". In the continued movement of the weighty member 9, the openings 16 will register with the slots 14 so as to permit the sound to be emitted in greater volume and simulate the letter "a", thereby completing the first sound of the syllable "ma".

At this time, the spring 24 is fully expanded so that through the connection of said spring, with the element 19 and the member 9, said element 19 is caused to move with the sleeve 9' along the tubular post 11, so that said sleeve and element are in the relative positions in said post substantially as seen in Figure 2 of the drawings. When the end portion of the sleeve 9' moves over the slots 14 in the tube wall, the volume of sound emitted is again restricted, such restricted volume emitted through the groove 18 again simulating the sound of the letter "m", and thereafter during the interval of movement equivalent to the distance between the sleeve and the element 19, the greater volume of sound simulating the letter "a" is again emitted, thus completing the sounding of the two syllable word "ma ma".

In the continued movement of the member 9, the lower end of the element 19 moves over the openings 14 in the tube wall and abruptly cuts off the emission of sound.

As this element 19 is not provided with the grooves or channels in its inner surface, it will be understood that the sound is completely cut off. When the openings 20, however, first register with the openings 14, there is an abrupt release of the sound and its emission, under considerable pressure in the larger volume through the openings 14, thereby sounding the letter "a" which continues until the other end portion of the element 19 again completely closes the openings 14, cutting off the emission of sound for a short period in the travel of said sleeve and then again permitting of the emission 125 130

of sound in maximum volume through said openings when the element 19 moves entirely below the openings in the final portion of the air expelling movement of the member 9. Thus, the phonetic articulation of the word "pa pa" is simulated and follows in close succession upon the sounding of the word "ma ma". By the provision of the separate sound control element 19 and the spring 10 connection of said element with the member 9, I secure the desired time interval between the sounding of the two words and also reduce the total necessary length of the "voice" in order to effect the sounding of the two words in a single air expelling movement of the member 9 to a minimum. At the same time, it will be seen from reference to Figure 1 of the drawings, that this arrangement insures the complete inflation of 15 the bellows chamber when the device is inverted from the position shown in Figure 2, so as to expand the flexible bellows wall 8.

From the foregoing description, considered in connection with the accompanying drawing, the construction and manner of operation of my present improvements will be clearly understood. It will be apparent from what has been said, that by the provision or the omission of the openings 16 and/or 20 and of the longitudinal grooves 17 and/or 18 in one or the other, or both, of the sound control parts 9' and 19, any one of a number of different combinations of the word syllables "ma" and 25 "pa" can be realistically sounded or simulated. Thus, for instance, by resorting to such obvious mechanical changes, it is possible to cause the device to simulate the phonetic articulation of the words "ma ma", "pa pa"; "pa pa, ma ma"; "ma ma, ma ma"; "pa pa, pa pa"; "pa pa, ma"; "pa, ma ma"; "pa pa"; "ma ma, pa"; "ma, pa" and "pa, ma".

However, it is thought that the arrangement which will preferably be adopted in most cases, is that illustrated in the drawings, whereby the two multi-syllable words "ma ma" and "pa pa" are successively sounded in a single operation of the device.

50. While I have herein shown an embodiment of the invention, which, in actual test, I have found to be highly satisfactory, it is nevertheless to be understood that more or less satisfactory results might be obtained by various alternative arrangements of the several cooperating elements and I accordingly reserve the privilege of resorting to all such legitimate changes in the form and construction of the several parts 55 as may be fairly embodied within the spirit and scope of the invention as claimed.

I claim:—

1. In a sound producing device, an air chamber, a reed, a weighty gravity movable member for expelling air from said cham-

ber through the reed, and means carried by said member controlling the emission of sound produced by the reed, said means consisting of independent sound emission control parts each having spaced portions to effect the simulation of the phonetic articulation of a multi-syllable word, and means connecting said control parts with each other and automatically acting during a single air expelling movement of said member to govern the time of operation of said control parts with respect to each other. 70

2. In a sound producing device, an air chamber, a reed, a weighty gravity movable member for expelling air from said chamber through the reed, independently operable sound emission control parts carried by said member and each having means to effect the simulation of the phonetic articulation of a multi-syllable word, and a yieldable connection between said sound control parts automatically acting during the air expelling movement of said member to permit of an operative movement of one of said parts with respect to the other with a resultant time interval between the articulation of the words. 80

3. In a sound producing device, an air chamber, a reed, a weighty gravity movable member to expel air from said chamber through the reed, a sound emission control part carried by said member, a second independent sound emission control part, and connecting means between said parts operating to hold the latter part stationary during the initial portion of the air expelling movement of said member and thereafter cause the unitary movement of said parts with the weighty member during the remaining portion of its air expelling movement to thereby produce a desired time interval between the effective operation of said control parts. 90

4. In a sound producing device, an air chamber, a reed, a weighty gravity movable member for expelling air from said chamber through the reed, a sound receiving chamber having an emission orifice in the wall thereof, a plurality of sound emission control parts each having means to cooperate with said orifice and effect the simulation of the phonetic articulation of a multi-syllable word, and means automatically operating during a single air expelling movement of said member to cause the effective operation of said control parts in timed relation to each other. 100

5. In a sound producing device, an air chamber, a reed, a weighty gravity movable member to expel air from said chamber through the reed, a tubular guide post for said member receiving the sound produced by said reed and having a sound emission opening in its wall, structurally independent, sound emission control parts movable 110

- on said post and each cooperating with said opening to effect the phonetic simulation of a word, and means automatically acting during a single operation of said air expelling member to initially cause a relative movement of said sound emission control parts and thereafter their unitary movement with the air expelling member to thereby produce a desired time interval between the 10 articulation of the words.
6. In a sound producing device, an air chamber, a reed, a weighty gravity movable member by which air is expelled from said chamber through the reed, a tubular guide 15 post for said member receiving sound from the reed and having an emission opening in its wall, a sound emission control part carried by said member and movable on said post, a second independent sound emission 20 control part, each of each control parts being provided with means to cooperate with said emission opening, whereby said parts effect the simulation of the articulation of phonetically different words, and a yield- 25 able connection between said control parts operating to hold the latter control part stationary during the initial portion of the air expelling movement of said weighty member and thereafter cause the unitary movement 30 of said control parts along the post during the remaining portion of the air expelling movement of said member, whereby a desired time interval intervenes between the successive articulation of the words.
- 35 7. In a sound producing device, a cylindrical casing, a gravity operable, longitudinally reciprocating air compressing and expelling member in said casing, a sounding reed through which the air is expelled, and 40 sound emission controlling means including two independently acting control parts movable as a unit with said air expelling member, and means automatically operating to effect a relative movement between said control parts during the air expelling movement 45 of said member.
8. In a sound producing device, a cylindrical casing, a gravity operable, longitudinally reciprocating air compressing and expelling member in said casing, a sounding reed through which the air is expelled, and sound emission controlling means including two independently acting control parts connected with said member for movement as a 50 unit therewith, the connecting means including means automatically operating to effect a relative movement between said control parts during the air expelling movement of said member.
- 55 9. In a sound producing device, a cylindrical casing, a gravity operable, longitudinally reciprocating air compressing and expelling member in said casing, a sounding reed through which the air is expelled, and sound emission controlling means including 60
- two control parts independently movable with respect to each other in the direction of movement of said air expelling member, and means governing the relative movement between said control parts and determining 70 the elapsed time interval between their effective operation.
10. In a sound producing device, a cylindrical casing having an air chamber therein and a gravity operable, longitudinally reciprocating member for expelling air from said chamber, a fixed guide for said member extending axially through the air chamber, a sounding reed through which the air is expelled, and sound emission controlling means 80 including independently acting control parts movable with said member upon said fixed guide, and means operatively connected with one of said control parts to hold the same relatively stationary during a portion of the 85 air expelling movement of said member to thereby produce a desired time interval between the functional operations of said control parts.
11. In a sound producing device, a cylindrical casing having an air chamber therein and a gravity operable, longitudinally reciprocating member for expelling air from said chamber, a sounding reed through which the air is expelled, a fixed guide for said member extending axially through the air chamber and having a sound emission aperture, and sound emission controlling means including a part on said member cooperating 90 with said emission aperture, a second independent control part relatively movable upon said guide and also adapted to cooperate with said emission aperture, and means connected with said air expelling member restraining the movement of the latter control 95 part during the initial portion of the air expelling movement of said member to thereby produce a desired time interval between the functional operation of said control parts.
12. In a sound producing device, a cylindrical casing having an air chamber therein and a gravity operable, longitudinally reciprocating member for expelling air from said chamber, a sounding reed through which the air is expelled, a fixed guide for said member extending axially through the air chamber and having a sound emission aperture, and sound emission controlling means including a part on said member cooperating 100 with said emission aperture, a second independent control part relatively movable upon said guide and also adapted to cooperate with said emission aperture, and a spring connecting the latter control part with said air expelling member and operating to restrain the movement of said control part during the initial portion of the air expelling movement of said member to thereby produce a desired time interval between the functional operation of the control parts.
- 130

13. In a sound producing device, a casing having an air chamber therein, a sounding reed, a gravity movable member for expelling air from said chamber through the reed, and sound emission control means including independently acting parts movable as a unit with said air expelling member and means automatically operating to hold one of said parts stationary during a portion of the air expelling movement of said member while permitting of its unitary movement therewith during another portion of such air expelling movement.
14. In a sound producing device, a casing having an air chamber therein, a sounding reed, a gravity movable member for expelling air from said chamber through the reed, a fixed guide for said member having a sound emission aperture therein, and sound emission controlling means including independently acting parts, one of said parts being carried by said member and the other mounted upon said guide for longitudinal movement and each of said parts having means cooperating with said sound emission

aperture, and means connecting the latter part with the air expelling member and automatically operating to hold said part stationary during a portion of the air expelling movement of said member while permitting of its unitary movement therewith during another portion of such air expelling movement.

15. In a sound producing device, a casing, a bellows in said casing having a weighty gravity movable head, a sounding reed through which air is expelled from the bellows by said head, and sound emission controlling means including independently acting parts movable as a unit with said head, and means connecting one of said parts with said head and operating to restrain such unitary movement of said part with the head during the initial portion of the air expelling movement of the latter.

In testimony that I claim the foregoing as my invention, I have signed my name hereto.

LEO J. GRUBMAN.
